UNITED STATES PATENT OFFICE.

CHARLES S. BROWN, OF RICE, WASHINGTON.

SILO-CHUTE.

1,197,259.

Specification of Letters Patent. Patented Sept. 5, 1916.

Application filed November 10, 1915. Serial No. 60,757.

To all whom it may concern:

Be it known that I, CHARLES S. BROWN, residing at Rice, in the county of Stevens and State of Washington, have invented a new and Improved Silo-Chute, of which the following is a specification.

My present invention, which relates to improvements in silos, is more particularly in the nature of an improved chute construction, adapted for being used with the ordinary types of silos having outwardly opening doors arranged in vertical series, and my said invention primarily has for its object to provide an improved construction 10 that includes a framing built up along the front or door side of the silo, a chute formed of sections, one section for each door of the silo, and means for adjusting the said sections successively, up or down, and in such a 15 manner that the operation of the silage is expeditiously accomplished.

Another object of my invention is to provide an improved means for discharging the silage from the silo, in which is included a 20 suitable framing built up along the front or door side of the silo, and composed of a series of vertically arranged hinged members that form platforms for their respective adjacent silo doors, means for gaining 25 access to the said platforms, and a chute formed of hinged sections, one section for each platform and silo door, and adapted for being readily and successively adjusted to the discharging positions by the operator 30 standing on the platform and other means for sustaining the chute sections in their several adjusted positions.

With other objects in view that will hereinafter appear my present invention embodies the peculiar construction and novel arrangement of the parts hereinafter fully explained, specifically pointed out in the claims and illustrated in the accompanying drawing, in which:—

Figure 1 is a vertical section of a portion of a silo with my improved construction of chute (shown in side elevation) operatively combined therewith, one of the chute sections being shown positioned for receiving 45 the silage discharging from the silo. Fig. 2 is a horizontal section taken on the line 2—2 on Fig. 1. Fig. 3 is a detail view on a slightly enlarged scale taken on the line 3—3 on Fig. 1. Figs. 4 and 5 are detail sections of slightly modified forms of my invention hereinafter specifically mentioned.

In the drawings, in which like numerals indicate like parts in all of the figures, 1 designates that portion of the wall of a silo, having the series of door openings 2, in vertical alinement, and doors 20 that are hinged to swing outwardly.

Built vertically along the door side of the silo is a wooden frame, consisting of a series of sets of horizontal joists 3, arranged in pairs, one pair of which is provided for each door opening 2, and made fast by angle plates 30 to the sills 21 of the door, one set of such angle iron connections being clearly shown in Fig. 2 of the drawings. The said framing also includes closed sides formed of boards 4 nailed to the joists 3 and a series of platforms in the nature of drop doors 5 hinged at one end to the upper edge of one sill and adapted, when lowered to rest on the opposite sill, the lowered position of one of the said platform doors being shown in Fig. 1. When at the up position the door 5 is held by a catch 50 see Fig. 1.

For readily gaining access to any of the platforms, ladder rungs 6 are secured to the door sills and to the doors, it being understood that after reaching an upper platform or landing the operator lowers the door for the platform below and so on.

So far as described, it will be noticed that the framing built up in front of the silo is in the nature of a vertically extended housing or chamber, and at this point it should be stated, the front wall of said chamber is in the nature of a vertically extended metallic chute, formed in sections, one of such sections being provided for each doorway for the silo.

The chute construction, in the preferred form, as is best shown in Figs. 1 and 2, includes a substantially semi-circular outer metal wall 7 that extends the full length of the framing and includes flat side extensions 70 the ends of which are bent at right angles to form angle plates 71 for extending over the adjacent outer edges of the said boards 4—4 (see Figs. 2 and 3). At suitable intervals and in vertical series, one for each silo doorway, the wall 7 has a substantially semi-circular spacing member 8 in the nature of a metal band the ends of which form side portions 80 that engage and are riveted to the flat side extensions 70 of the member 7 and whose extremities are turned inwardly to form angle flanges 81, which extend over the outer adjacent edges of the

board sides to which they are made fast by bolts 82, that also secure the angled plates 71 of the member 7 which latter are bulged to lap the flanges 81, as is clearly shown in Fig. 3. The chute construction also includes a series of hinged members 73 that form half portions of the complete chute when they are swung up to a closed position as shown at X, Fig. 1, and serve as chute or conveyer members when they are dropped down to the position Y in Figs. 1 and 2. Each member 73 has its lower end connected to the upper end of the next chute section or member 73 by a hinged joint 74 and the said lower end is of partial elbow shape as at 74, to form a substantial closure at the opposite edges when the said hinged chute or trough is at the said down position, the said lower edge being also so cut that when the member 73 is swung up to the closed position such lower edge moves down into the metal spacing member or ring 8, as is clearly shown in Fig. 1 and to provide for a closed joint between the upper end 73^a of the member 73 and the ring 8, the latter has an offset as at 74^a to form a seat for the said upper end 73^a, which in practice has a suitable catch 73^b for holding it to its locked position.

In the preferred structure, the chute or trough-like sections are sustained at their pendient positions by chains 11.

By reason of the peculiar construction and arrangement of the parts so far described and illustrated in Figs. 1, 2 and 3 of the drawings, a simple and easily adjusted means for discharging the silo is provided.

In filling the silo, the same is done pneumatically by applying a blower to the lower end of the chute and by a U tube connection on the upper end of the chute that discharges into the top of the silo, as shown in my Patent No. 1,145,550 for silo door system, dated July 6, 1915.

In discharging the silo, the uppermost hinged section of the chute is swung down into the uppermost doorway of the silo and the silage is raked out and discharged through a large chute member 73 from whence it passes into the closed chute through which it drops to the ground into a suitable wagon or other receptacle, it being also understood that the chute sections 73 are successively lowered from the top to the bottom of the chute when discharging the silo.

In Fig. 4 is illustrated a somewhat modified arrangement of my invention and in this form the chute, instead of being formed with hinged sections, as in the preferred form, has, at each doorway of the silo, a lateral discharging mouth C, that is normally closed by a drop cover plate D, which in practice may have a spring latch to hold it closed.

When using a chute, as shown in Fig. 4,

a long funnel C' is employed for connecting the mouth C with the silo, the discharging end of such funnel extending over the door sill of the silo as shown.

In Fig. 5 is shown a further modification of my invention and in this form the hinged chute section is also used, and it differs from the chute section 73 in the preferred form, in that it is long enough to extend into the silo doorway and rest on the door sill.

From the foregoing description taken in connection with the drawings the complete operation, the manner in which my invention is utilized and the advantages thereof will be readily apparent to those skilled in the art to which it relates.

What I claim is:

1. The combination with a silo having a series of vertical alined doorways having outwardly opening doors; of a discharging chute located outside of the silo and in line with the vertical alined doorways, the said chute comprising two half sections, one section of which forms an outer wall that extends the full height of the chute, the other section consisting of a series of portions, each hingedly connected at its lower end to the fixedly held part of the chute and to swing inwardly and outwardly, one of the said hinged portions being provided for each doorway, means for holding the said hinged portions in suspension with their outer ends adapted to receive the silage passed out of their respective doorways, the said hinged portion when swung up to the vertical position forming a continuation of the discharging chute.

2. The combination with a silo having a series of vertical alined doorways having outwardly opening doors; of a discharging chute located outside of the silo and in line with the vertical alined doorways, the said chute comprising two half sections, one section of which forms an outer wall that extends the full height of the chute, the other section consisting of a series of portions, each hingedly connected at its lower end to the fixedly held part of the chute and to swing inwardly and outwardly, one of the said hinged portions being provided for each doorway, means for holding the said hinged portions in suspension with their outer ends adapted to receive the silage passed out of their respective doorways, the said hinged portion when swung up to the vertical position forming a continuation of the discharging chute, and a locking detent for each of the hinged portions for engaging the fixed portions of the said chute, to hold the hinged portions up to their vertical or closed position.

3. The combination with a silo having a series of door openings and an outwardly opening door for each opening and ar-

ranged successively one above the other; of a chamber along the door side of the silo formed of a framing comprising closed side portions, a platform including a trap door 5 in line with each doorway, a series of ladder rungs, one projected from each door sill, the silo body forming the back wall of the said chamber, a chute that forms the front wall of the said chamber and which consists 10 of two half sections, an outer one and an inner one, the outer section being fixedly connected to the closed side portions of the framing and extending the full length of the chamber, the inner section of the chute 15 comprising a series of vertical aligned chute like members, each hingedly secured to the outer section to swing outwardly and downwardly, means for holding the said chute-like members at their down position, where- 20 by to adapt them to receive the silage discharged from the silo openings and to convey the said silage to the discharging chute

and means for holding the hinged chute sections locked to their vertical or closed position.

4. The combination with a silo having a succession of doorways each having a door; a framing built along the door side of the silo, a chute connected to the framing, said chute being formed of sections that swing 30 down to receive the material from the doorways of the silo, one section for each doorway, spacing members between each adjacent pair of chute sections, said members forming a part of the chute, hinge connec- 35 tions that join the upper ends of the spacing members with the chute sections above them and means for locking the upper ends of the said chute sections over the lower ends of the said spacing members.
